Primary Examiner — Paula Allen Greene*(74) Attorney, Agent, or Firm* — Katten Muchin
Rosenman LLP(57) **CLAIM**

I claim the ornamental design for a microphone, as shown and described.

DESCRIPTION

FIG. 1 is a perspective view of a microphone showing my new design with the legs retracted,
 FIG. 2 is a front view thereof,
 FIG. 3 is a rear view thereof,
 FIG. 4 is a left-side view thereof,
 FIG. 5 is a right-side view thereof,
 FIG. 6 is a top view thereof,
 FIG. 7 is a bottom view thereof;
 FIG. 8 is a perspective view thereof with the legs extended;
 FIG. 9 is a front view thereof,
 FIG. 10 is a rear view thereof,
 FIG. 11 is a left-side view thereof,
 FIG. 12 is a right-side view thereof,
 FIG. 13 is a top view thereof; and,
 FIG. 14 is a bottom view thereof.
